FREEZING MOLD FOR ICE STICKS

Avin Columbus Johnson and Charles C. Oliver,
New Orleans, La.

Application January 7, 1946, Serial No. 639,584

3 Claims. (Cl. 62—108.5)

1

Our invention relates to a device intended for household refrigerators and the main object thereof is to provide means for making icicles or long narrow sticks of ice for convenient use in thermos and other bottles or the like in preference of the now prevalent ice cubes or crushed ice for insertion through the narrow necks of the bottles. It is believed that such a contrivance would be welcome as an addition to refrigerators in all homes.

It should be noted that this freezing mold or tray is shaped so that it can be used in ordinary refrigerating units.

This ice stick mold or double tray is very easy to handle and each tray can be used singly or both trays together as they will come apart easily being separated by a metal dividing plate.

The formed ice sticks can be readily removed from the trays in the usual manner by application of water, and no waste will occur.

In the accompanying drawing, one embodiment is illustrated, and

Figure 1 shows in top plan view both trays assembled.

Figure 2 is a transverse section in larger scale taken along line 2—2 of Figure 1.

Figure 3 is a top plan view of the bottom tray with the cover or dividing plate partially removed.

Figure 4 shows a fragmentary vertical length section of the top tray.

As best shown in Figures 2 and 4, the invention consists of a top tray 10 and a bottom tray 11 the one fitting snugly in the other and being adapted to be placed singly or both together in the ordinary ice pan of a refrigerator.

The top or upper tray 10 preferably made entirely of rubber or similar plastic material and cast or pressed in one piece, built on a full length bottom 9, has three chambers formed by a front and a rear transom 12, 13 of the same or different lengths varying preferably between 3½ and 4 inches. Each of said chambers contains several compartments 14, 9 being indicated on the drawing, of the same width, about ¾ inch and ½ inch depth and are separated by the partitions 15 extending the entire length of each chamber. These sizes may vary to suit conditions. These partitions, transoms and bottom are molded as a unit with a rolled edge or bead 16 on all four sides at the top edge. The side walls 18 and the rear end wall 19 are all perpendicular to the bottom 9, but the front wall 20, Figure 4, is preferably inclined at a 70° angle against the bottom 9, this for the purpose of

2

facilitating removal of the top tray 10 from the bottom tray 11.

The bottom tray 11 is likewise preferably made entirely of rubber built up on its flat bottom 23 with perpendicular side and rear walls 24, offset near the upper edge to form a flat seat or shelf 27 to accommodate the bottom of the top tray 10. The edge is finished off with a bead 26 similar to the top tray and this bead facilitates the removal of the bottom tray 11 with or without the top tray.

A vertical length section is shown in Figure 4 of the top tray indicating the perpendicular rear wall 19 and the slanting front wall 20 having an inclination of about 70° against the bottom 9. When the top and bottom trays are assembled as in Figure 2 a flat dividing plate 30 of aluminum or other metal is inserted between them, entirely filling the seat 27 of the lower tray 11 and on this plate the top tray rests. Its function, being a good heat conductor, is to speed up the freezing action on the water in the trays, which, when made of rubber or similar plastic material, are inferior heat conductors. A finger hold 31 is shown at the front edge of the plate consisting of a cut-out of its edge. However, the trays may be made entirely of metal, in which case any dividing plate 30 would be superfluous.

The bottom tray is arranged with chambers 30 and compartments 14 similarly to the top tray and accordingly provided with transoms 13, and longitudinal partitions 15. Both trays together may therefore produce 51 or more sticks of ice.

It is to be understood that the invention as here disclosed is not limited to the details here described and shown but that the same may be varied without departing from the spirit of the invention as defined by the subjoined claims.

We claim:

40. 1. A freezing mold for producing ice sticks in refrigerators, comprising a top tray and a bottom tray, each forming a separate unit and made of resilient material; each of said trays having a flat bottom, surrounding side walls, transoms and length partitions providing a plurality of long, narrow compartments wherein to produce the ice sticks; said bottom tray having a shelf-like formation having an upstanding vertical edge extending along the four walls adapted for seating the top tray therein, a removable metal plate inserted on said shelf like formation beneath the top tray, the function of said plate being to increase the freezing ability of the mold.

45. 2. A freezing mold for producing ice sticks in refrigerators, comprising a resilient top tray and

a resilient bottom tray each forming a separate unit; each of said trays having a flat bottom, surrounding side walls, transoms and length partitions providing a plurality of long, narrow compartments wherein to produce the ice sticks; said bottom tray having a shelf-like formation extending along the four walls adapted for seating the top tray, a removable metal plate inserted on said formation beneath the top tray, the function of said plate being to increase the freezing ability of the mold, the top edges of the side walls being turned to form a bead to facilitate lifting of the trays.

3. A freezing mold for use in refrigerators comprising a resilient top tray and a resilient bottom tray, each of said trays having a bottom and side walls, transoms and partitions providing a plurality of compartments, said bottom tray in-

cluding a shelf-like formation having an upstanding edge extending along said walls for seating the top tray therein and a removable plate on said shelf-like formation beneath said top tray.
